UNITED STATES PATENT OFFICE.

GEORGE D. SPIELMAN, OF LANCASTER, OHIO.

IMPROVEMENT IN CAR-COUPINGS.

Specification forming part of Letters Patent No. 146,408, dated January 13, 1874; application filed August 16, 1873.

To all whom it may concern:

Be it known that I, GEORGE DANIEL SPIELMAN, of Lancaster, in the county of Fairfield and State of Ohio, have invented a new and Improved Car-Coupling, of which the following is a specification:

My invention consists of a horizontal bar, arranged transversely to the car in a horizontal slot in the end of the draw-head, and pivoted at its middle to the draw-head, and having a hook on one end to engage the end of a similar bar on the draw-head of the other car to be coupled, having a similar hook, which similarly engages the end of the first-mentioned bar, not having a hook. The slots in the draw-head are shaped so that the coupling bars can be raised at the ends having the hooks, and depressed at the other ends, to allow the hook ends to rise up over the other ends for coupling, and the hooked ends of the bars are provided with chains to lift them up. The draw-heads are also chambered out above and below the slots, for the coupling-bars to receive the ordinary coupling-links, and pin-holes are provided for the ordinary coupling-pins, so that cars with my improved coupling can also be coupled to cars having the ordinary couplings.

Figure 1 is a horizontal section of the draw-bars, and a plan of the coupling-bars and hooks, according to my improvement, the section being taken on the line $x x$ of Fig. 2. Fig. 2 is a side elevation of Fig. 1. Fig. 3 is an end elevation of one of the draw-heads; and Fig. 4 is a perspective view of one of the coupling-bars and hooks.

A represents the draw-heads; B, the horizontal slots in the ends; C, the coupling-bars; D, the hooks; E, the pivots of the said bars; F, the pins for the ordinary links; G, the chains for lifting the coupling-bars; I, ascending and descending walls of the slots B, to

allow the draw-bars to swing vertically to engage and disengage them by the hooks; and J, recesses to admit the ordinary links to be coupled by pins F.

It will be seen that the hook of one bar encounters the end of the other bar not provided with a hook, and rises up on it by the curved end a , while, at the same time, the said end swings down in consequence of the hook at the other end rising on the end of the other bar. The inclines I, or rather the widened portions of the slots at the inclines, allow the bars to swing in this manner.

The bars C are made wide and strong in the middle, where they are pivoted, and extend into the slots far enough to receive the pivots E, behind the ordinary coupling-pins F, and they are slotted, at F' F', sufficiently for both of said pivots to allow them to swing upward and down, as needed for engaging and disengaging with each other.

The coupling is very strong and durable, and will couple self-actingly, as well on curves as on straight lines, and will uncouple, in case the cars run off or shift, very much relatively to each other.

I propose to employ a lever to pull up the chain for uncoupling the cars, the lever being pivoted to the cars so that a person standing on the ground can uncouple the cars by pulling down on the lever.

Having thus described my invention, I claim as new and desire to secure by Letters Patent—

The draw-heads A, having end slots B and pivots E, combined with coupling-bars C, having hooks D, curved end a , and slots F', as and for the purpose described.

GEORGE DANIEL SPIELMAN.
